UNITED STATES PATENT OFFICE.

FRANK E. BALDEN, OF PORTLAND, OREGON.

FURNACE.

1,226,167.

Specification of Letters Patent. Patented May 15, 1917.

Application filed November 1, 1916. Serial No. 128,871.

To all whom it may concern:

Be it known that I, FRANK E. BALDEN, a citizen of the United States of America, residing at Portland, in the county of Multnomah, in the State of Oregon, have invented certain new and useful Improvements in Furnaces, of which the following is a specification, reference being had to the accompanying drawing.

10 My invention relates to furnaces generally, and particularly to fire box boiler furnaces. Its object is to provide means in a furnace for rendering the heat generated in the medial portion of the fire box available 15 as a means for promoting a higher degree of combustion in the furnace. This end I accomplish by providing above the grate a super-heater, which, being exposed to the direct heat of the fire above the grate and 20 receiving a supply of air from below the same, effects the result of super-heating the air and discharging it at the forward end of the super-heater into the combustion chamber of the furnace, thereby stimulating the 25 draft and producing a hot, clear fire.

My super-heater is preferably adjustable to different positions above the grate bars, and thereby affords means for cutting down the capacity of the furnace when it is desired 30 to use it for mild weather. This result is accomplished in conjunction with its super-heating function.

In the accompanying drawing,

Figure I is a side elevation, partly in section on line I—I of Fig. II of the fire box end of a boiler showing my super-heater in side elevation, but with the side exposed partially broken away to exhibit the interior construction of the super-heater.

40 Fig. II is a transverse section on the line II—II of Fig. I.

Fig. III is a partial view similar to Fig. II, showing one side of the fire box banked up to cut it out of service in order to reduce the size of the fire.

Fig. IV is a view similar to Fig. III, but showing the super-heater moved to one side in order to effect a greater reduction in the size of the fire.

50 Referring to the numerals on the drawing, 1 indicates the wall of a fire box communicating with boiler tubes 2 through a boiler head 3 and provided with a grate 4. The shape and dimensions of the fire box, its 55 combination with a boiler, and the construction of the grate are all non-essential de-

tails, and, in the form in which they are illustrated in the drawing, are presented only by way of example.

My invention consists of a super-heater 5 adapted to be introduced into the interior of the fire box 1 above the grate 4, where it is supported, preferably with an adjustability, upon any suitable supporting members such for example as shelves 6.

65 The super-heater may be of any suitable and preferred shape, but I prefer to make it in the shape of an inverted V shaped trough as shown for example in comparison of Figs. I and II. The member 5 preferably extends 70 lengthwise from front to rear of the interior of the fire box and in cross-section is of the general triangular contour shown for example in Fig. II. The rear wall 7 of the super-heater is solid while the front wall 8, 75 at the opposite end thereof, is provided with a wide aperture 9. Between the front and rear walls I preferably provide one or more partition walls 10, each having an aperture 11 corresponding substantially to the aperture 80 9 in the front wall 8. The bottom of the super-heater is preferably open and, extending as it does across a part of the bars of the grate 4, is adapted to receive influx 85 of air from below the grate through the spaces provided between the bars. The super-heater resting upon its shelves 6 may be embedded in the mass of incandescent material 12 which during the operation of the furnace is supported upon the grate 4. Under such conditions the walls of the super-heater are brought to a high temperature 90 with the effect of producing a constant flow of air from below the grate through the several compartments, defined by the partitions 10, within the super-heater and its discharge through the aperture 9 into the combustion chamber of the furnace. The result is to stimulate and promote combustion to a high degree of perfection within 95 the furnace.

A distinct advantage of my device is that in connection with its super-heating function, it is adapted to act as a reducer to the area of the grate. For example in Fig. III 105 it is shown as medially located above the grate, so as to reduce the grate capacity by one half. This is accomplished by filling in the fire box on one side of the super-heater with dead matter, such for example, 110 as ashes 14. By this means the fire 15 is accommodated within one half the grate ca-

pacity of the fire box, while the super-heater, exposed on one side to the heat of the fire 15, is enabled thereby to exert its super-heating function to supply super-heated air 5 to the interior of the fire box for the promoting of combustion therein. The effect is to make it possible to carry a small fire within the fire box with excellent efficiency.

10 Fig. IV is designed only to illustrate the transverse adjustability of the super-heater whereby increased reduction of the effective area of the grate may be attained. In all other respects the description of the operation 15 employed with respect to Fig. III applies to Fig. IV.

The operation of my device requires little further description than that given above. After the super-heater is set in position the 20 fire is built around it, or against it, as the case may be, and the super-heating effect is produced automatically without the necessity of attention upon the part of the fireman. The doorway 16 shown in Fig. I is, 25 of course, in practice closed as usual by a door not illustrated.

If the efficient area of the grate is to be reduced, the filling 14 is put in place and af-

terward the fire is built and maintained in the usual way, the operation of the super-heater being the same whether the whole or only a part of the grate capacity be employed.

What I claim is:

1. As a new article of manufacture, a super-heater comprising an open bottomed member provided with imperforate side and rear walls, and with a perforated front wall.

2. As a new article of manufacture, a super-heater comprising an open bottomed member provided with imperforate side and rear walls, and with perforated front and partition walls.

3. The combination with a furnace or the like and its grate, of a super-heater having an open bottom adapted to rest upon the grate, and having imperforate side and rear walls, and a perforated front wall.

In testimony whereof, I have hereunto set my hand in the presence of two subscribing witnesses.

FRANK E. BALDEN.
